ELASTIC BONDED LACE

Jean Claude Fontanille, Rue des Capucins,
Le Puy (Haute-Loire), France

Filed Nov. 17, 1969, Ser. No. 20,113

Term of patent 14 years

Int. Cl. D5—02

U.S. Cl. D92—1

FIG. 1 is a front elevational view of an elastic bonded lace showing my new design over a dark background; the background being for purposes of illustration; and

FIG. 2 is a rear elevational view thereof shown over a dark background which background is seen through the apertures at the top of the lace as well as beyond the top and bottom edges of the design, the background being for purposes of illustration.

I claim:

An ornamental design for an elastic bonded lace, as shown and described.
